FOLDING LEG BRACKET HINGE

Andrew D. Sheffer, Brighton, Mich.

Application August 26, 1947, Serial No. 770,633

2 Claims. (Cl. 311—99)

1

This invention relates to pivotal mounting hinge means for folding legs and the like, and more particularly to folding leg hinges for securing to the corners of articles of furniture and other structures which are supported on legs.

A main object of the invention is to provide a novel and improved hinge means for folding legs which is very simple in construction, easy to install, and providing a firm supporting cooperation of the legs with respect to the article to which they are attached.

A further object of the invention is to provide an improved folding leg hinge which is inexpensive to manufacture, neat in appearance and sturdy in construction.

A still further object of the invention is to provide an improved hinge device for attaching folding legs to articles such as tables and the like, said hinge device allowing the legs to be easily folded into compact relation with the article to which they are attached and providing a very steady and secure support for the article when they are unfolded.

Further objects and advantages of the invention will become apparent from the following description and claims, and from the accompanying drawings, wherein:

Figure 1 is a plan view of a sheet metal blank employed to form a corner hinge bracket for a folding leg in accordance with the present invention.

Figure 2 is a side elevational view of a corner hinge bracket formed from the blank of Figure 1, shown attached to a leg.

Figure 3 is a cross-sectional view taken on line 3—3 of Figure 2.

Figure 4 is a view taken on line 4—4 of Figure 3.

Figure 5 is a top plan view of a corner hinge bracket according to the present invention formed as a casting.

Figure 6 is a view taken on line 6—6 of Figure 5.

Figure 7 is a cross-sectional view taken on line 7—7 of Figure 5.

Figure 8 is a top plan view of a double leg hinge bracket constructed in accordance with the present invention.

Figure 9 is a view taken on line 9—9 of Figure 8.

Figure 10 is a cross-sectional view taken on line 10—10 of Figure 8.

Figure 11 is a perspective view showing the double leg hinge bracket of Figures 8, 9 and 10.

2

employed to connect the legs of a bench to the seat portion thereof.

Figure 12 is a bottom plan view of a table employing corner hinge brackets according to the present invention for foldably connecting the legs of the table to the top thereof, said legs being shown in folded positions.

Figure 13 is an elevation view of a corner hinge bracket generally similar to that shown in Figures 5, 6 and 7 but involving a modification thereof.

Figure 14 is a view taken on line 14—14 of Figure 13.

Referring to the drawings, and more particularly to Figures 1 to 4, 11 designates a generally circular sheet metal blank which is radially cut, as shown at 12 and is adapted to be folded at respective radial lines 13, 14 and 15 to form the corner angle member shown in Figures 2, 3 and 4. The sectors of the blank are designated respectively at 16, 17, 18 and 19. Sector 16 is formed with a U-shaped slit at 20 to define a rectangular tab 21, said tab being folded at right angles to the sector on line 22. Sector 17 is formed with a U-shaped slit at 23 to define another tab 24, said tab 24 being bent at right angles to sector 17 on line 25. Sector 17 is notched at 26 to provide clearance for tab 21 when the blank is folded so that the sector 17 underlies the sector 16 when the corner angle member is formed as above described.

Sector 19 is formed with an arcuate slot 27 having a straight end portion 28 angled radially inwardly of the blank with respect to the arcuate portion which is substantially concentric to the axis of the blank.

When the blank is folded on the crease lines

13, 14 and 15, as above described, side sector 19 is at a right angle to side sector 18, and sectors 18 and 19 are downwardly and outwardly inclined with respect to horizontal top sector 16, said top sector being rigidly secured by any suitable means to the underlying sector 17. When the elements are thus secured, tab 21, tab 24, sector 19 and sector 18 define a generally rectangular downwardly and outwardly-directed socket at the corner of the device in which the top end of a leg 29 is adapted to be received when said leg is in the upstanding position shown in broken lines in Figure 2. Passing through the upper portion of leg 29 is a headed bolt 30 which passes slidably through slot 27. Threaded on the end of bolt 30 is a wing nut 31 adapted to lock the leg 29 in an adjusted

position with respect to the corner bracket device.

The bracket device is formed with suitable apertures, such as shown at 32 for securing said device by means of suitable fastening means to the corner of a table or other article. Figure 12 illustrates the use of the corner brackets at the four corners of a table. As shown in Figure 12, the legs 29 may be swung to parallel inwardly adjacent positions with respect to the skirt portions 33 of the table and locked in said inward positions by means of the wing nuts 31. To set up the table, the wing nuts are loosened and the legs are swung outwardly until they reach abutting positions against the respective corners formed by the sectors 19 and 18. The bolts 30 are then in alignment with the straight slot portions 28, allowing the inner ends of the legs to be moved upwardly into seated positions in the rectangular enclosures defined by tabs 21 and 24 and the corners between sectors 19 and 18. By tightening the wing nuts 31 the legs may be rigidly locked in said seated positions. Due to the downwardly flaring relation of the legs, afforded by the downwardly and outwardly inclined directions of sectors 19 and 18 the final configuration of the legs provides a high degree of stability for the table.

In the embodiment of Figures 5, 6 and 7, the corner hinge bracket is fabricated as a three sided body including vertically disposed plates 35 and 36 at right angles to each other and secured together at their confronting edges and a horizontally disposed plate 37, the vertically disposed plates 35 and 36 flaring outwardly with respect to the horizontally disposed plate 37. One of the vertically disposed plates 36 is formed with an arcuate slot 27 having a straight end portion 28 extending from a point intermediate the ends of the slot toward and terminating at a point spaced from the horizontally disposed plate 37, and an arcuate portion extending transversely from the intermediate point toward and terminating at a point spaced from the free side edge of the vertically disposed plate 36. The slot is adapted to receive a hinge pin 30 carried by the leg 29 whereby travel of the hinge pin 29 from the terminating end of the arcuate portion of the slot 27 toward the terminating end of the straight portion thereof results in the leg 29 being shifted from a collapsed position to an extended position. Depending from the horizontally disposed plate 37 is a right-angled rib 38, including two tabs, each of the tabs being disposed transversely of the adjacent one of the vertically disposed plates and in spaced relation with respect to the other one of the vertically disposed plates and defining with the adjacent portions of the vertically disposed plates the socket for receiving the top end of the leg 29. Suitable openings 39 are formed in the horizontally disposed plate 37 and in the vertically disposed plates 35 and 36 for securing the corner bracket to the corner portion of a table or other article to be supported.

As shown in Figures 13 and 14, the slot 27 and its straight portion 28 may be counterbored at the outer surface of a side flange 36', as shown at 40, to provide clearance for the head of bolt 30 when the bracket is secured inside the corner formed by a table top, or other article to be supported, and the depending skirts or aprons carried at the margins of the articles, in the manner disclosed in Figure 12. Also, as shown in Figures 13 and 14, the side flanges 36' and 35' of

the bracket are right angularly disposed to each other and to the top wall 31. However, flanges 36' and 35' have inner surfaces which are downwardly and outwardly tapered in thickness to allow the legs 29 to flare downwardly when the table or other article is set up and to still provide a right angled corner configuration to closely fit into the corner of the article formed by its top and its depending side skirts.

The arcuate slot 27 and straight portion 28 may be provided in either of the two side flanges of the bracket so that either right or left hand brackets may be formed.

In the embodiment of Figures 8 to 11, a double bracket 41 is illustrated, for securement to a bench top 42, a trestle, or other relatively narrow article, to be supported at its ends. The bracket 41 is formed with a top 43, an end flange 44, and side flanges 45 and 46. Each of the side flanges 45 and 46 is formed with an arcuate slot 27 having the aforementioned straight end portion 28, and the top 43 is formed with depending right-angled ribs 47, 47 defining sockets for the top ends of the legs 29 at the corners of the bracket. The bench top 42 is secured to the top 43 of a double corner bracket 41 at each end of the bench. The legs 29 are foldable to positions parallel to the side edges of the bench in the same manner as described in connection with the preceding embodiments of the invention. The respective flanges 44, 45 and 46 are in downwardly flaring relation with respect to the top 43, allowing the corner legs 29 to be in similarly flared relation when the article is set up and thereby providing a high degree of stability for the article.

While certain specific embodiments of hinge brackets for folding legs have been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A folding leg bracket hinge comprising a horizontally disposed plate, a first vertically disposed plate arranged along and secured to one side edge of said plate, a second vertically disposed plate arranged along and secured to one end edge of said horizontally disposed plate, a first tab arranged in parallel spaced relation with respect to said first vertically disposed plate and dependently carried by said horizontally disposed plate, and a second tab arranged in parallel spaced relation with respect to said second vertically disposed plate and dependently carried by said horizontally disposed plate, said tabs and the adjacent portions of said first and second vertically disposed plates together forming a rectangular socket for embracingly receiving one end of a table leg, one of said vertically disposed plates being provided with a closed slot for slidably receiving a hinge pin carried by the one end of said table leg, said slot including a straight slot portion extending from a point intermediate the ends thereof toward and terminating at a point spaced from said horizontally disposed plate and an arcuate slot portion extending from said intermediate point toward and terminating at a point spaced from said horizontally disposed plate.

2. A folding leg bracket hinge comprising a horizontally disposed plate, a first vertically disposed plate arranged along and secured to one

side edge of said plate, a second vertically disposed plate arranged along and secured to one end edge of said horizontally disposed plate, a first tab of a length shorter than said first vertically disposed plate arranged in parallel spaced relation with respect to said first vertically disposed plate and dependingly carried by said horizontally disposed plate, and a second tab of a length shorter than said second vertically disposed plate arranged in parallel spaced relation with respect to said second vertically disposed plate and dependingly carried by said horizontally disposed plate, said tabs being of equal length and with the adjacent portions of said first and second vertically disposed plates forming a rectangular socket for embracingly receiving one end of a table leg, one of said vertically disposed plates being provided with a closed slot for slidably receiving a hinge pin carried by the one end of said table leg, said slot including a straight slot portion extending from a point intermediate the ends thereof toward and terminating at a point spaced from said horizontally disposed plate and an arcuate slot portion ex-

tending from said intermediate point toward and terminating at a point spaced from said horizontally disposed plate.
